UNITED STATES PATENT OFFICE.

BRYSON D. HORTON, OF DETROIT, MICHIGAN.

ELECTRICAL SWITCH.

1,129,569.

Specification of Letters Patent. Patented Feb. 23, 1915.

Application filed November 1, 1913. Serial No. 798,679.

To all whom it may concern:

Be it known that I, BRYSON D. HORTON, a citizen of the United States, residing at Detroit, in the county of Wayne and State 5 of Michigan, have invented certain new and useful Improvements in Electrical Switches, of which the following, taken in connection with the accompanying drawings, is a full, clear, and concise description.

10 My present invention relates to certain improvements in that type of switch which is commonly referred to as iron clad, that is—an electrical switch in which the switch mechanism is mounted within a metallic 15 casing, so designed as to prevent or reduce hazard or risk incident to devices of the kind which are used to control high electric currents, such a switch is illustrated and described in my previous application 20 Serial No. 759,005, filed April 5, 1913, upon which construction, the present invention is an improvement.

One of the objects of my present invention is to provide the metallic casing with a 25 hinged cover which is self acting in maintaining its closed position so that the electrical connections and conductor parts are unexposed.

Another object of my present invention is 30 to provide a novel form of bearing for the switch operating handle or crank.

In the accompanying drawings, I have 35 illustrated the improvements which form the subject of my present invention.

Figure 1, illustrates an iron clad switch in side elevation with the hinged cover in dotted line position when open to permit of access to the interior thereof. Fig. 2, is a front interior view of the switch casing 40 with the cover partly broken away. Fig. 3 is a detail of one of two like parts which constitute a bearing member for the switch operating handle.

In detail, 1 indicates the body or receptacle portion of the casing, 2 a cover which is hinged to said body portion at 3. The hinged portions of the receptacle consists of coöperating rearward extensions 4 and 5 formed integral with the cover and body 50 portions respectively, the pivots 3 extending therein and forming the journal therefor. In order to prevent the cover from being opened and left in this position so that the interior switch mechanism will be exposed 55 and to prevent any danger incident thereto, I provide a projection 6, extending rearwardly and cast integral with the hinged portion 4 which projection acts as a limiting stop permitting the cover to be opened only to a definite fixed extent. The cover 2 when opened to its fullest extent, assumes the dotted line position illustrated in Fig. 1. In this position, the rearwardly extending projection 6 abuts or engages the top surface of the receptacle 1 and prevents the lid or cover from being oscillated to any great extent in opening direction. As soon as the hand is removed from the cover, the cover will swing on its pivot to closed position of its own weight, owing to the fact that the cover has not reached or passed the center of gravity with respect to the pivotal point 3 of the hinge. In this manner, it is impossible for the user to leave the switch cover open after once having gained access to the receptacle for any desired reason.

Within the metallic housing 1, is mounted the switch mechanism with an extending operating arm or crank which provides for exterior manipulation thereof. The switch mechanism may be conveniently described as consisting of a pair of switch jaw contacts 7, coöperating knife switch blades 8, the latter being carried by the cross head 10 provided with an eye 11 through which projects the end 12 of an operating crank or handle 13. In order to mount the operating crank or handle, the side of the casing is slotted at 14 to permit the passage and positioning of the handle within the side of the casing. In order to form a substantial journal or bearing for the arm, I have devised novel inexpensive means which consists of sheet metal stampings formed into cup like members 15 (see Fig. 3). These cup-like members are provided with flanged portions 16 having perforated ears 17 and two of such members comprise the bearing for the handle. The bearing is associated with the handle portion before the latter is bent into final finished form, that is,—the handle is projected through apertures extending through the center of the cup members and thereafter bent into U-shape form as illustrated. When this has been accomplished, the handle and cup members are assembled in their proper relation on each side of the wall of the casing, while the handle is being inserted through the slot 14 into its proper position, whereupon the cup members are riveted together with the side of the casing by rivets 18. In order to substantially fill up the

cutout or slotted portion 14, and in order to add further rigidity to the parts, ears 19 are provided which are pinched together at 20 as shown. A bearing of this description 5 is not only inexpensive to manufacture, but serves as a substantial article of its kind and provides an increased bearing and alining member for the handle.

While I have illustrated certain details 10 of construction, I do not wish to be limited with respect thereto, as it is manifest that certain changes may suggest themselves to those skilled in the art without departing from the scope and spirit of the invention, 15 as set forth in the appended claims.

Having thus described my invention what I claim as new herein and desire to secure by Letters Patent is:

1. In a switch of the character described, 20 a housing provided with a slotted side, a substantially U-shaped operating handle for the switch mechanism and a coöperating pair of sheet metal bearing members assembled upon said operating handle, said operating handle and bearing members adapted 25 to be mounted in the slot of the side of the casing, said bearing members when posi-

tioned being made fast to the respective sides of the slotted side of the casing and providing bearing and alining means for 30 said handle.

2. A bearing for a switch handle, comprising two like sheet metal stampings adapted to be attached to opposite sides of one side of the switch casing and having 35 bearing portions parallel with but removed from the plane of the side of the casing.

3. A bearing for a switch handle comprising complemental cup-shaped parts formed from sheet-metal and provided with coincident circumferential flanges, said flanges serving as means for attachment to a switch casing, the center of the cup-shaped parts being provided with openings to receive the operating handle and to serve as a bearing 45 therefor.

In witness whereof I have hereunto set my hand in the presence of two subscribing witnesses this 29th day of October, 1913.

BRYSON D. HORTON.
